M. WEINER

ADJUSTABLE SHIRT SLEEVE

Filed Aug. 28, 1926

Fig:1

Fig:4

Fig. 3

A detailed anatomical diagram of a plant stem's longitudinal section. The stem is represented by a vertical line with a wavy, irregular boundary on the left side. Several features are labeled with numbers: '10' points to a circular structure near the top; '8' points to a dashed elliptical shape; '7' points to another dashed elliptical shape; and '5' points to a small circle at the bottom right containing a smaller circle with a cross inside. The diagram illustrates the internal tissue arrangement and specific anatomical details of the stem.

UNITED STATES PATENT OFFICE.

MORRIS WEINER, OF CHICAGO, ILLINOIS, ASSIGNOR TO, DOROTHEA WEINER, OF CHICAGO, ILLINOIS.

ADJUSTABLE SHIRT SLEEVE.

Application filed August 28, 1926. Serial No. 132,275.

It is an object of this invention to provide a shirt wherein the total sleeve length may be adjusted a reasonable amount to fit the particular wearer while maintaining the 5 appearance of the shirt the same under all conditions of adjustment. More particularly it is an object of this invention to produce the adjustment by varying the relative position of the cuff with respect to the sleeve, 10 the cuff being permanently attached to the sleeve.

The attainment of these and other objects will be apparent from this specification taken in conjunction with the drawings 15 forming a part thereof.

In the drawings, Figure 1 is a front view of one of the sleeves with the cuff adjusted for maximum length; Figures 2, 3, and 4, are side views illustrating the cuff in different 20 adjusted positions.

The shirt sleeve indicated at 1, forming part of my improved shirt has the usual opening at 2, and button hole at 3. At 4 and 5 are indicated two buttons for a 25 purpose hereinafter to be explained. The cuff is formed of an integral piece of material which is folded upon itself and the two coinciding edges sewed together and to the shirt sleeve at 6. The other end of the 30 sleeve is sewed to the shirt in the ordinary way.

At 7, 8, 9, and 10 and at 7', 8', 9', and 10' are shown a series of button holes in alignment lengthwise of the sleeve and spaced 35 as shown. With the cuff in the position shown in Figures 1 and 2, a cuff link is passed through 10 and 9, and through 10' and 9'. It is to be noted that the holes 8, 9, are on the inner side of the cuff and 40 hence not exposed to view. Thus the cuff of my improved shirt presents an outward appearance the same as the ordinary shirt cuff.

The total sleeve may be adjusted in length 45 by moving the outer portion of the cuff so that the hole 10 is opposite the hole 8 as shown in Figure 3, or opposite the hole 7, in which latter case the hole 9 will just avoid coming on to the front portion of 50 the cuff. In the adjusted position a cuff link is passed through the hole 10 and either 7 or 8 as the case may be.

The total sleeve length may be further 55 shortened by rolling the cuff along the sleeve until the button hole 10 is on the lower in-

ner side of the cuff and opposite the button 4, as shown in Figure 4. The button holes 7, 8, 9, and 10 are so spaced that with 10 in the position shown, 7 and 9 are opposite each other, and the hole 8 just avoids coming 60 on to the front portion of the shirt. A cuff link is then passed through the holes 9 and 7. The button 4 is passed through the button hole 10, to keep the lower portion of the cuff against the sleeve and thus prevent 65 flapping of the cuff.

A narrow strip of material 12 is provided at one edge of the sleeve as shown in Figure 1. This piece of material folds back and is out of sight. The button 5 is sewed 70 to this strip adjacent the button 4. When the shirt is worn in a position other than that shown in Figure 4, the button 4 is passed through the button hole 3, as in the ordinary shirt. With the cuff in the position shown in Figure 4, the button 5 is passed through the hole 3 and the same button is further passed through the hole 10' which is now opposite that button as 10 is 75 opposite 4.

It may be seen from the drawings that the loop forming the cuff always presents the same outward appearance regardless of the position to which the cuff has been adjusted, the adjustment being obtained by shifting 80 the position of the cuff with respect to the sleeve.

In compliance with the requirements of the statutes, I have herein described a preferred embodiment of my invention. I do 85 not however wish to be limited to the precise construction set forth, the same being shown for illustrative purposes only.

What I claim as new and desire to secure 90 Letters Patent upon is:

1. An adjustable shirt sleeve comprising a 95 cuff consisting of a looped piece of material sewed to the shirt sleeve, the loop being open along its lateral edges, and means whereby the loop may be adjustably held so that it 100 overlaps the sleeve on one side thereof for variable predetermined distances from the point where it is sewed to the sleeve.

2. An adjustable shirt sleeve comprising a 105 cuff consisting of a looped piece of material sewed to the shirt sleeve, the loop being open along its lateral edges, means whereby the loop may be adjustably held so that it overlaps the sleeve on the outside thereof for variable predetermined distances from the 110

point where it is sewed to the sleeve, and means for retaining the overlapping portion of the loop against the sleeve.

3. In combination, a sleeve, a cuff formed of a continuous piece of material folded upon itself and the opposite longitudinal edges sewed together and to the sleeve, a button hole formed on the outer part of the cuff, a plurality of button holes formed on the inner part of the cuff, said button holes being in alignment lengthwise of the sleeve, whereby fastening means may be passed through the outer button hole and different ones of the inner button holes to shift the position of the cuff with respect to the sleeve.

4. In combination, a sleeve, a cuff formed of a continuous piece of material folded upon itself and the opposite longitudinal edges sewed together and to the sleeve, a button hole formed on the outer part of the cuff, a button hole formed on the inner part of the cuff, a button on the shirt sleeve, said button and said button holes being in alignment lengthwise of the sleeve and equal distances from the point where the sleeve and cuff are joined, whereby the cuff may be held in either of two positions at will, one of said positions being with the cuff extended and the two button holes opposite one another, and the other position being with the cuff shifted lengthwise of the sleeve so that the button and the first mentioned button hole are opposite one another, and an additional button hole on the cuff in alignment with the other two and spaced so that when the cuff is in the second mentioned position that button hole and the second mentioned button hole are opposite each other.

5. In a shirt, a sleeve having a tubular cuff at the end thereof permanently attached thereto, the lateral ends of the cuff being open so that the cuff may be shifted lengthwise of the sleeve, and means for holding the cuff in various shifted positions lengthwise of the sleeve on the outside thereof, whereby the combined length of the sleeve and cuff is varied while the amount of cuff portion exposed is maintained constant.

6. In a shirt, a sleeve having a tubular cuff at the end thereof permanently attached thereto, the lateral ends of the cuff being open so that the cuff may be shifted lengthwise of the sleeve, means for holding the cuff in various shifted positions lengthwise of the sleeve on the outside thereof, whereby the combined length of the sleeve and cuff is varied while the amount of cuff portion exposed is maintained constant, and means whereby the portion of the cuff overlapping the sleeve is held against the sleeve.

7. A soft cuff consisting of a piece of material folded on itself to form a closed loop with its meeting longitudinal extremities sewed to a shirt sleeve, three button

holes in alignment laterally of the cuff and close to the lateral edge of the cuff, the lateral edges of the doubled material being open along the portion of the cuff between the three button holes, so that fastening means may be passed through one of the button holes and either of the other two.

8. In a shirt, a sleeve having a cuff in the form of a closed loop at the end thereof permanently attached thereto, said cuff being shiftable lengthwise of the sleeve, means for holding the cuff in various positions, said means comprising three button holes formed in the cuff, two on one side of the loop of the cuff and one on the other, said button holes being in alignment lengthwise of the sleeve, so that fastening means may be passed through any two of the three button holes to hold the cuff in any of three positions with respect to the sleeve.

9. In a shirt, a sleeve having a looped cuff at the end thereof permanently attached thereto, said cuff being shiftable lengthwise of the sleeve, means for holding the cuff in various positions, said means comprising three button holes formed in the cuff, two on one side of the loop of the cuff and one on the other, said button holes being in alignment lengthwise of the sleeve, so that fastening means may be passed through any two of the three button holes to hold the cuff in any of three positions with respect to the sleeve, and means cooperating with one of said button holes when fastening means have been passed through the other two, for holding the end of the cuff against the sleeve.

10. In a garment, a sleeve having at the end thereof a soft cuff consisting of a continuous piece of material folded upon itself and the opposite longitudinal edges sewed to the sleeve, means for adjustably securing a point on the outer side of the folded material to either of two points on the inner side of the folded material, said three points being in alignment lengthwise of the sleeve, one of the points on the inner side being as far from the juncture of the sleeve and cuff as is the point on the outer side, and the other point on the inner side being a different distance from the juncture of the cuff and sleeve than are those two points.

11. In a garment, a sleeve having at the end thereof a soft cuff consisting of a continuous piece of material folded upon itself and the opposite longitudinal edges sewed to the sleeve, three button holes formed in the cuff adjacent one of the lateral edges of the cuff, two of said button holes being formed on one side of the fold, and the third being formed on the other side of the fold, so that fastening means may be passed through the third button hole and either of the other two, three button holes formed in the cuff adjacent the other lateral edge of the cuff, said second mentioned three button

holes being spaced identically with said first mentioned three button holes, so that the button holes that are secured together at one of the lateral edges of the cuff may be secured to the button holes that are secured together at the other lateral edge of the cuff, the lateral edges of the cuff being open adjacent the button holes, so that the same inner part of the opposite lateral edges of the cuff are in contact with one another when the opposite lateral edges are secured together, regardless of which two button holes are used.

12. In combination with a shirt sleeve, a soft cuff sewed thereto consisting of an inner and an outer portion slidable with respect to one another lengthwise of the sleeve secured together to form a loop extending lengthwise of the sleeve, and means formed in the cuff for holding the inner and outer portions in adjusted positions with respect to each other.

13. In combination with a shirt sleeve, a soft cuff consisting of a looped piece of material sewed to the sleeve along the longitudinal edge of the loop, a button-hole on the

outside of the loop, two button-holes on the inside of the loop, said three button-holes being in lateral alignment and near the lateral edge of the loop, the lateral edges of the loop being open so that the outer portion of the loop may slide over the inner portion whereby said first mentioned button-hole may be brought opposite either of the last-mentioned button-holes at will.

14. In combination with a shirt sleeve, a soft cuff consisting of a looped piece of material sewed to the sleeve along the longitudinal edge of the loop, the loop being open along the lateral edges so that the outer portion of the loop may slide over the inner portion on the outside of the sleeve, whereby the combined length of the cuff and sleeve is varied while the amount of cuff portion exposed is maintained constant, and three or more button-holes formed in the cuff in lateral alignment for holding the cuff in various positions lengthwise of the sleeve.

In testimony whereof I have hereunto affixed my signature.

MORRIS WEINER.
